UNITED STATES PATENT OFFICE.

EMANUEL F. BROWN AND SAMUEL M. MILLER, OF NEBRASKA, ASSIGNORS
OF ONE-THIRD TO WILSON S. DRESBACH, FRANK P. DRESBACH, AND
CHARLES DRESBACH, OF EAST RINGGOLD, OHIO.

STRAW-STACKER.

SPECIFICATION forming part of Letters Patent No. 291,674, dated January 8, 1884.

Application filed April 13, 1883. (No model.)

To all whom it may concern:

Be it known that we, E. F. BROWN and S. M. MILLER, of Nebraska, Pickaway county, Ohio, have invented an Improvement in Straw-Stackers, of which the following is a specification.

The invention will first be described in connection with the drawings, and then pointed out in the claim.

Figure 1 of the drawings is a side elevation, 10 and Fig. 2 a cross-section, of that portion of a stacker to which our invention is applied.

a represents the bed-frame of the stacker; *e*, a circular way or track; *h*, a turn-table having rim *f* and flanges *g*, which work on said track; 15 *i*, rollers which are mounted on the brackets *j*, are geared, and hold the table to the track. This turn-table *h* carries the shaft *m* in bearings *n*, and on this shaft are mounted the arms *o* of the lower section of the stacker-frame, by 20 means of V-shaped supports *p*, with the bearings *q*.

The shaft *m* carries a fast pinion, *s*, which

gears with a master-wheel, *t*, on a shaft, *u*, arranged in the axis of the turn-table, and this latter shaft carries the fast sprocket-wheel *v*, 25 which may be connected with suitable mechanism to drive the stacker from the thrasher.

The shaft *m* also carries a chain-wheel, *z*, from which the lower roller, *a'*, of the endless carrier *b'* of the stacker is to be driven by a 30 chain, *c'*.

Having thus described all that is necessary to a full understanding of our invention, what we claim as new and of our invention is—

The combination of the turn-table *h*, having 35 rim *f*, with flanges *l* and *g*, the brackets *j*, the cross-beam *k*, and the rollers *i*, substantially as shown and described.

EMANUEL F. BROWN.
SAMUEL M. MILLER.
